(57) **CLAIM**

The ornamental design for an electric drill, as shown and described.

DESCRIPTION

FIG. 1 is a front perspective view of an electric drill showing my new design;

FIG. 2 is a side view thereof;

FIG. 3 is the opposite side view of FIG. 2;

FIG. 4 is a front view thereof;

FIG. 5 is a rear view thereof;

FIG. 6 is a top view thereof;

FIG. 7 is a bottom view thereof;

FIG. 8 is a front perspective view of an alternative embodiment of an electric drill showing my new design;

FIG. 9 is a side view thereof;

FIG. 10 is the opposite side view of FIG. 9;

FIG. 11 is a front view thereof;

FIG. 12 is a rear view thereof;

FIG. 13 is a top view thereof; and,

FIG. 14 is a bottom view thereof.

The power cord is shown broken away in the drawing views in order to indicate that a specific length of power cord forms no part of the claimed design.

The stipple shading seen on the trigger and button in the FIGS. 8, 9, 10, 11, 12, and 14 views is used to denote a color contrast between these elements and the body of the electric drill.

The broken line showing of environmental structure is for illustrative purposes only and forms no part of the claimed design.
